UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

SEWING MACHINE.

1,423,205.

Specification of Letters Patent.

Patented July 18, 1922.

Application filed November 21, 1918. Serial No. 263,453.

To all whom it may concern:

Be it known that I, GEORGE S. GATCHELL, a citizen of the United States, residing at Roselle Park, in the county of Union and 5 State of New Jersey, have invented certain new and useful Improvements in Sewing Machines, of which the following is a specification, reference being had therein to the accompanying drawings.

10 This invention relates to sewing machines and, more particularly to machines of the type in which the frame comprises a standard, a work-supporting arm free at one end and at its other end joined to said standard, 15 and a bracket-arm carried by the standard and overhanging the work-supporting arm. The stitch-forming instrumentalities of a machine of this type operate at the free end of the work-supporting arm and derive power 20 from a main-shaft usually journaled within and transversely of the standard and having an out-board projection to which is fixed a hand-wheel; the latter being necessarily disposed remote from the stitching point.

25 In the use of a machine of this character, the operator, in finishing off a seam, is obliged to reach for the remote hand-wheel and turn it forwardly until the needles of the machine are down and then backwardly 30 a half-revolution to elevate the needles from the work and free the looper from the needle-loops so that the work may be withdrawn without so disarranging the needle-threads that a new seam cannot be easily 35 started.

The operator's necessity of bending over and reaching from the stitching point at the front end of the machine to the hand-wheel adjacent the standard, each time the 40 needle-threads are to be severed and the finished work removed, needlessly tires and wastes the time of the operator and slows up production.

It is therefore a desideratum of no small 45 importance that the manually operated or controlled parts of the machine be constructed and arranged so that they may be reached and manipulated with the least possible exertion and loss of time, and so that 50 their operation will require the least number of movements on the part of the operator.

The present invention has for an object to 55 provide a sewing machine of the type in which the work is fed toward the standard,

with a hand-wheel which is connected to the stitch-forming and feeding mechanisms and is within easy reach of the operator for manipulation.

A further object of the invention is to 60 provide the machine with a readily accessible hand-wheel which may be manipulated to free the needles and needle-loops from the work in the shortest possible space of time and with the least exertion on the part of 65 the operator.

To the attainment of the above and other objects as will hereinafter appear, the machine frame, if of the cylinder bed type, may have fixed thereto a bracket which projects 70 forwardly from the standard in spaced relation to the work-supporting arm and at its free end carries a bearing in which a hand-wheel is journaled in a position below the bracket-arm, forwardly of the standard, and 75 within easy reach of one of the operator's hands. The hand-wheel is operatively connected with the main-shaft of the machine preferably by means of suitable speed-multiplying means, whereby a given angular 80 movement of the hand-wheel will produce a greater angular movement of the main-shaft, thus making manual manipulation of the main-shaft less tiring to the operator and reducing to a minimum the necessary 85 motions incident to the freeing of the needle-loops from the looper preparatory to removal of the work from the machine.

In the accompanying drawings, Fig. 1 is 90 a side elevation of a machine embodying the invention. Fig. 2 is a top plan view of the machine illustrated in Fig. 1. Fig. 3 is a front elevation of the parts of the machine adjacent the stitching point.

In the preferred embodiment of the invention as illustrated, the machine as to all details not specifically referred to herein-after is constructed substantially in accordance with the disclosure in my copending application Serial No. 185,446, filed August 10, 1917. The machine frame comprises a base 1 from which rises the standard 2 sustaining the overhanging bracket arm 3 which terminates in the hollow head 4 in which are journaled the reciprocating 100 needle-bar 5 and presser-bar 6 carrying, respectively, the eye-pointed needles 7 and the presser-foot 8.

The needles 7 cooperate in the usual manner with the threaded looper 8' mounted at 110

the forward end of the sliding and oscillating looper shaft 9 journaled lengthwise of and within the hollow work-supporting arm 10 which is free at its forward end and at its rearward end is joined to the standard 2 at a point above the base 1, whereby a free space about the work-arm is provided to permit the sewing up of tubular work.

10 The presser-foot 8 cooperates with the fulling and main feed-dogs 11 and 12, respectively, to full-in the work in advance of the needles 7 and feed the stitched work away from the needles and toward the standard 2.

15 The needle-bar 5 is connected by a link 13 to a crank arm 14 at the front end of the oscillating needle-actuating shaft 15 journaled within and lengthwise of the bracket-arm 3. At its rearward end the shaft 15 carries a crank-arm 16 which is connected by the pitman 17 to a crank 18 formed in the main-shaft 19 journaled in the standard 2 transversely of the plane of the standard and bracket-arm. The main-shaft is driven by the usual belt-pulley 19' fixed thereto.

30 As previously constructed, machines which feed the work toward the standard have been provided with the hand-wheel mounted upon the main-shaft at the rear of the machine, thus making it necessary for the operator to lose much time in bending over and reaching for the relatively remote hand-wheel preparatory to the usual operation of turning the hand-wheel backwardly a half revolution to free the looper from the needle-loops.

35 To obviate this waste of effort and loss of time on the part of the operator, it is proposed to mount the hand-wheel adjacent the stitching point, so that the operator may quickly shift his hand sidewise from stitching position and grasp the hand-wheel without elevating his entire arm or reaching 40 to the main-shaft at the rear of the machine. The hand-wheel is therefore located below the level of the bracket-arm 3 and in advance of the standard 2, in which position it is particularly easy of access to the operator.

45 The hand-wheel 20 may be conveniently mounted in the desired location by being fixed to a short transverse shaft 21 journaled in the boss 22 at the forward end of the arm 23 of a suitable bracket screwed at its rear end to the side of the standard 2. The hand-wheel shaft 21 carries a pulley-wheel 24 which is connected by the belt 25 to a similar pulley-wheel 26 fixed to the main-shaft 19. The pulley-wheel 26 is preferably made smaller than the pulley-wheel 24, having, in the present instance, a diameter of substantially one half the diameter of the pulley-wheel 24. To prevent objectionable slippage of the belt 25 it may be

provided with the usual belt clips 27 which mesh with suitable transverse slots 28 in the belt contacting surfaces of the pulleys. The belt may be encased within a suitable belt-housing 29.

70 By virtue of the speed-multiplying connection between the hand-wheel 20 and main-shaft 19 it will be understood that the operator, in reversing the machine, need impart but one quarter revolution to the hand-wheel to effect the necessary half revolution of the main-shaft. This may be done by a single oscillatory movement of the operator's hand whereas, heretofore, a plurality of oscillatory motions of the operator's hand have been required to effect the desired half revolution of the main-shaft. The arm 23 of the bracket is spaced from the work supporting arm 10 and does not interfere with the accumulation of tubular work about the work-supporting arm.

75 The invention is not to be understood as limited to a machine of the "cylinder bed" type but may also be used to advantage in connection with flat bed and various other 80 types of machines.

85 Having thus set forth the nature of the invention, what I claim herein is—

1. A sewing machine comprising a standard and a work-supporting arm extending therefrom, stitch-forming mechanism adjacent the free end of the arm, a main-shaft mounted in the standard, operative means connecting the stitch-forming mechanism and the shaft, a hand-wheel mounted in advance of said standard and independently of the work-supporting arm, substantially at the level of and adjacent the stitch-forming mechanism, and operative means connecting the hand-wheel and main-shaft.

90 100 105 110 115 120 125 130

2. A sewing machine formed with a standard, a bracket-arm, and a work-supporting arm free at one end and at its opposite end joined to said standard with a free space about said work-supporting arm permitting of sewing up of tubular work, stitch-forming and work-feeding mechanisms incorporated in said frame, said feeding mechanisms operating to feed the work lengthwise of the work-supporting arm, a main-shaft journaled in said standard for driving said stitch-forming and work-feeding mechanisms, a forwardly projecting bracket carried by said standard, a rotatable hand-wheel carried by said bracket adjacent the free end of the work-supporting arm, and an operative connection between said hand-wheel and main-shaft.

3. A sewing machine formed with a standard, a bracket-arm, and a work-supporting arm free at one end and at its opposite end joined to said standard with a free space about said work-supporting arm permitting the sewing up of tubular work, chain-stitch-forming mechanism incorporated in said

- frame and including a reciprocating needle and a looper, work-feeding mechanism incorporated in said frame and operating to feed the work lengthwise of the work-supporting arm, a main-shaft journaled in said standard for driving said stitch-forming and work-feeding mechanisms, a forwardly projecting bracket carried by said standard and spaced from said work-supporting arm, a 5 rotatable hand-wheel carried by said bracket adjacent the free end of the work-supporting arm, and a speed multiplying connection between said hand-wheel and main-shaft, whereby a given angular movement 10 of the hand-wheel will produce a greater angular movement of the main-shaft.
4. A sewing machine comprising a standard and a work-supporting arm extending therefrom, stitch-forming mechanism adjacent the free end of the arm, a main-shaft 20 mounted in the standard, operative connections from the shaft to the stitch-forming mechanism, a bracket secured to the standard and extending to a point adjacent the stitch-forming mechanism, a hand-wheel rotatably mounted in said bracket adjacent the stitch-forming mechanism and an operative connection between the hand-wheel and the main-shaft. 25

In testimony whereof I have signed my name to this specification.

GEORGE S. GATCHELL.
